UNITED STATES PATENT OFFICE

2,146,000

SCREW STOPPER FOR RECEPTACLES

Stanley Hutchcroft Williams, London, England

Application October 19, 1937, Serial No. 169,877
In Great Britain July 3, 1937

3 Claims. (Cl. 215—73)

- This invention is for improvements in or relating to screw stoppers for receptacles of the type requiring to be tightly closed against the escape through the closed stopper of vapour or gas evolved from the contents of the receptacles; for example and more particularly the invention relates to screw stoppers for receptacles for the package of ether and like highly volatile liquids.
- 5 The object of the invention is to provide an improved construction of screw stopper for receptacles of the type referred to, which will be characterized by a high order of efficiency as regards vapor or air-tightness and at the same time will incorporate a simple and convenient form of dispensing means for the contents of the receptacle.
- 10 A form of screw stopper for receptacles of the type referred to above is known which comprises a screwed neck constituting the body of the stopper, a correspondingly screwed closure cap for the neck and a rigid soft-metal sealing element arranged to be interposed between the cap and the neck and to be clamped gas-tightly by 15 the cap through the intermediary of a clamping element intervening between the sealing element and the cap, on to a seating provided to receive it on the neck, the sealing element being in the form of a hollow cup-like cone disposed with its 20 axis parallel to the neck, the seating for the element and similarly the clamping element therefor being of conical form to correspond with the conicity of the sealing element whereby the clamping element, the sealing element and the 25 seating therefor all snugly interfit within one another when the stopper is in closed condition, and the sealing element and the clamping element both being separate entities in the sense of being devoid of connection either with one 30 another or with the stopper body on the one hand and the closure cap on the other. The cup-like cone constituting the sealing element may, for example, be composed of lead and may be disposed in the stopper with the open end or base 35 outermost with respect to the interior of the receptacle. It is found that a stopper of this construction is highly effective for the purposes of prevention of escape through the closed stopper of vapour or gas evolved from ether or a like 40 highly volatile liquid contained in a receptacle fitted with the stopper and on account of the conical form of the sealing element and the corresponding conicity of the seating therefor on the one hand and of the clamping element on the 45 other, these parts are rendered self-centering.
- 50

relatively to one another in the operation of effecting closure of the stopper whereby the full efficiency of the stopper is assured.

The present invention relates to screw stoppers of this known class, but whereas with the known stoppers the construction has been one in which no means are provided for dispensing the ether or other contents of the receptacle fitted with the stopper, the improved stopper according to the present invention incorporates such means in the form of a dispensing nozzle carried upon the clamping element and projecting therefrom through an opening provided to receive it in the crown of the cap, the bore of the said nozzle extending also through the clamping element so that by insertion of a pointed instrument through the bore, the soft-metal cone constituting the sealing element of the stopper may be pierced for the dispensing through the nozzle of the ether or the like liquid content of the receptacle and the nozzle being preferably fitted, moreover, with a gas or vapour-tight closure cap whereby the gas or vapour-tight closure of the receptacle may again be effected after a use of the dispensing means.

With this improved construction of stopper in accordance with the present invention, it is possible where desired or necessary to dispense with the need for unscrewing the cap of the stopper once it has been screwed hard home to effect the initial closure of the receptacle, that is, in cases where it is not required to empty the receptacle in a single gross pouring out operation but on the contrary to dispense the ether or the like directly from the receptacle; in this event all that is requisite is to remove the closure cap from the dispensing nozzle, pierce the sealing element by inserting a pointed instrument through the bore of the nozzle and effect the dispensing of the liquid therethrough with replacement, after the necessary quantity of liquid has been dispensed through the nozzle, of the closure cap therefor.

The accompanying drawing illustrates a convenient and preferred embodiment of the invention by way of example.

In the drawing,

Figure 1 is an external side elevation of the improved stopper of the invention;

Figure 2 is a longitudinal central section through the stopper;

Figure 3 is a plan of Figure 1, and

Figure 4 is an exploded view showing the component parts of the stopper in the order in which they are assembled on the receptacle.

Like reference characters refer to like parts in the various figures.

The stopper comprises a screwed neck 1, a screwed closure cap 2, a hollow conical lead sealing element 3 seated on a conical seating 4 provided to receive it at the outer end of the throughway of the neck 1 and a loose clamping element 5 of corresponding conicity to the seating 4 but of inverted relationship thereto so as to co-operate with said seating 4 in gas-tightly clamping the cone 3 in position between the neck 1 and the cap 2, the element 5 intervening between these parts and transmitting the thrust from the underside of the cap 2 to the cone in position upon the seating 4.

Projecting from the crown of the clamping element 5 and extending therefrom through the crown of the cap 2 is a tubular extension 6 constituting in accordance with the present invention a dispensing nozzle for the contents of the receptacle fitted with the stopper. This nozzle, the bore of which extends as shown through the body of the clamping element to the apex or point thereof and which may if desired be shorter than the length in which it appears in the drawing, so as not to project so far from the crown of the cap 2, or if preferred, longer, is provided with a closure cap 7 screwed on to the end of it and incorporating a lead washer 8 against which the preferably reduced extremity of the nozzle bears with a gas-tight sealing fit when the cap 7 is screwed firmly home on the nozzle.

The opening in the crown of the cap 2 through which the nozzle 6 extends is at the centre of the cap and is coaxial with the cap. The cap is in turn coaxial with the sealing and clamping elements 3, 5 and the crown of the clamping element is spherical as shown. Consequently, the cap 2 is caused to bear upon the clamping element along a surface of engagement which is circular and concentric with the sealing element, the clamping element and the conical seating surface 4 of the neck 1 and in the result the parts are all mutually self-aligning under the thrust of the cap 2.

In the crown of the cap 2 is a slot 9 for the purpose of enabling the cap to be screwed hard home or to be readily loosened for removal from the neck when required, with the aid of a turning tool of the nature of a screw-driver forked at the end to accommodate the nozzle 6. If desired, instead of slotting the cap for this purpose, it may be formed with peripheral flats for engagement with a spanner or the like.

The neck 1, clamping element 5, nozzle 6, cap 2 and cap 7 of the stopper may be composed of any suitable hard and preferably non-corrodible metal such for instance as brass, and the sealing element 3 may be composed of any suitable soft metal such for example as lead.

The washer 8 may similarly be composed of any suitable material for the purpose, for example leather, rubber or lead as already referred to, but lead or a like soft metal is preferred as it tends to give a more efficient seal.

Separate dispensers for receptacles for the package of ether and like highly volatile liquids are already known, to be fitted on to the neck of the stopper of the receptacle after the closure cap thereof has been removed. Such separate dispensers, however, are disadvantageous in that their use involves the exposure of the volatile content of the receptacle to the external

atmosphere in the operation of fitting on the dispenser. With the improved dispensing stopper of the present invention, this drawback is obviated, for, as stated, it is unnecessary therewith to remove the main closure cap of the stopper in order to bring the dispenser into use; all that is necessary is to remove the small stopper from the end of the dispenser and then pierce the sealing element within.

What I claim as my invention and desire to secure by Letters Patent of the United States is:—

1. A screw stopper for receptacles for the package of ether and like volatile substances, comprising in combination a screwed neck, a correspondingly screwed closure cap therefor, a rigid soft-metal sealing element in the form of a hollow cone arranged to be clamped gas-tightly by the cap through the intermediary of a clamping element also of conical form on to a conical seating on the neck, the clamping element and sealing element being separate entities from one another and also from the neck on the one hand and the cap on the other, and a dispensing nozzle carried upon the clamping element and projecting therefrom (when the parts of the stopper are in assembled position) through an opening in the crown of the cap, the bore of the nozzle extending also through the clamping element so that by insertion of a pointed instrument through the bore, the sealing element may be pierced. 30

2. A screw stopper for receptacles for the package of ether and like volatile substances, comprising in combination a screwed neck, a correspondingly screwed closure cap therefor, a rigid soft-metal sealing element in the form of a hollow cone arranged to be clamped gas-tightly by the cap through the intermediary of a clamping element also of conical form on to a conical seating on the neck, the clamping element and sealing element being separate entities from one another and also from the neck on the one hand and the cap on the other, a dispensing nozzle carried upon the clamping element and projecting therefrom (when the parts of the stopper are in assembled position) through an opening in the crown of the cap, the bore of the nozzle extending also through the clamping element so that by insertion of a pointed instrument through the bore, the sealing element may be pierced, and a replaceable gas-tight closure cap for the nozzle. 45

3. A screw stopper for receptacles for the package of ether and like volatile substances, comprising in combination a screwed neck, a correspondingly screwed closure cap therefor, a rigid soft-metal sealing element in the form of a hollow cone arranged to be clamped gas-tightly by the cap through the intermediary of a clamping element also of conical form on to a conical seating on the neck, the clamping element and sealing element being separate entities from one another and also from the neck on the one hand and the cap on the other, a dispensing nozzle carried upon the clamping element and projecting therefrom (when the parts of the stopper are in assembled position) through an opening in the crown of the cap, the bore of the nozzle extending also through the clamping element so that by insertion of a pointed instrument through the bore, the sealing element may be pierced, and a replaceable gas-tight closure cap for the nozzle incorporating a soft-metal washer to ensure the gas-tightness of the cap. 70
